RESILIENT WHEEL.

1,163,575.

Specification of Letters Patent. Patented Dec. 7, 1915.

Application filed December 2, 1911. Serial No. 668,499.

To all whom it may concern:

Be it known that we, CHARLES F. WEBBER, of Boston, in the county of Suffolk, and EDMUND PERLEY HEMENWAY, of Winchester, 5 in the county of Middlesex and State of Massachusetts, have invented certain new and useful Improvements in Resilient Wheels, of which the following is a specification.

10 This invention relates to an improvement in resilient wheels.

The object of the invention is to provide a resilient wheel having independent resilient members or portions arranged to assume a predetermined load, and means for relieving the resilient portion of the wheel from any undesired burden or overload in excess of said predetermined load.

Accordingly, a feature of the invention 20 contemplates the provision of a wheel having a rigid rim, and a sectional tread composed of independent resilient members arranged to assume a predetermined load, said rim being arranged to assume the load when 25 the supporting power of said resilient members has been overcome, thus protecting said resilient members against injury by overloading.

The invention will be described in the following specification and the novel features 30 thereof will be pointed out in the appended claims.

In the accompanying drawing, Figure 1 is a transverse vertical section of a portion 35 of a wheel embodying one form of the invention, Fig. 2 is a side elevation of the same, with one side of the barrel of the wheel removed, Fig. 3 is a fragmentary bottom plan view of the periphery of the wheel showing one form of sectional tread, and Fig. 4 is a similar view showing a modified 40 form of tread.

As illustrated in the drawing, the present embodiment of the wheel comprises a hub 45 10 having annular flanges 12 and 14, to which the annular sides 16 and 18 of the body or barrel of the wheel are secured by bolts 20 passing through said sides and flanges. The side 16 is formed with an annular shelf 22 which fits the outer periphery of a shoulder 24 on the inner face of the side 18; and the end face of said shelf engages a correspondingly located annular finished surface 26 on the inner face of the side 18 adjacent to the ledge or shoulder 24. The 55 shelf 22 constitutes the inner wall of a chamber 28, within which the resilient elements of the wheel, to be hereinafter described, are housed.

In the present embodiment of the invention 60 the sectional tread of the wheel is composed of independent reciprocatory elements provided with tension and compression springs.

The rim 30 is preferably formed integrally with the side 16, and is counterbored at 32 to receive the side 18 to form the rigid tread of the wheel, and constitutes the outer annular wall of the chamber 28. The rim 30 is provided with holes 34, through which 70 plungers 36 are adapted to pass. These plungers fit the holes 34 and may be of any desired size and shape to hold correspondingly shaped tread sections or blocks 38. As illustrated in Figs. 2 and 3 the plungers and 75 holes are rectangular in shape and located in staggered relation in two rows extending around the entire rim of the wheel, although it should be understood that any number of rows may be employed. Another convenient 80 form of sectional tread is shown in Fig. 4, in which the plungers 40 are cylindrical in form and fit correspondingly shaped holes 42 in the rim 43, and carry cylindrical tread sections or blocks 45.

The plungers 36 are conveniently formed 85 of cups having inwardly projecting tubular stems 44, which are affixed to the outer ends of rods 46 in any suitable manner. If desired the cups and rods may be made integral. The tread sections 38 fit and are secured in the cups 36 and project radially outward beyond said cups to form the traction surfaces of the wheel. These sections 38 may be made of rubber, wood, or any 90 other suitable material, and when worn down to the edges of the cups can be replaced. The inner ends of the cup stems 44 abut against shoulders 50 on the rods 46. These rods extend radially of the wheel with 100 their inner ends projecting through holes 52 in the shelf 22, and provided with nuts 54, which bear against the inner face of the shelf 22 and limit the outward movement of the rods under the action of the resilient 105 members. The sectional tread of the wheel preferably comprises independent elements having springs associated therewith ar-

ranged to assume part of a predetermined load, and other springs arranged to assume the remainder of the predetermined load, said sectional tread coöperating with the rim of the wheel in such a manner that when the load exceeds the predetermined amount said rim will assume the excess load and the resilient sectional tread will be protected against further strain or distortion.

The rods 46 are preferably provided intermediate their length with shoulders 56, which are in engagement with yokes 58 embracing said rods. These yokes are provided with laterally projecting apertured ears 60, to which one end of the tension member 62 are connected. These tension members are in the form of coiled springs formed with hooks at each end for ready engagement with a coöperating element. The outer ends of said springs are preferably connected to eye-bolts 64 secured in the rim 30. As illustrated in the present embodiment of the invention there are two double rows of eye-bolts 64, and the tension members are connected to diagonally located eye-bolts in each double row.

Embracing the inner ends of the rods 46 are heavy compression springs 66, which may be surrounded for a portion of their length by split sleeves or cups 68 driven into and bearing against the shelf 22. These sleeves yieldingly embrace the springs 66 and prevent them from slipping along the rods 46, thus preventing rattling of said springs.

From the construction above set forth it will be noted that the wheel comprises a sectional resilient tread, the sections of which are independent and held out from the rigid rim of the wheel by springs, preferably tension springs constructed to carry a part of any proper load for which the car is designed. As the wheel rolls along successive plungers come into action, so that a traction surface of considerable extent is always available, which readily adapts itself automatically to the surface over which the wheel is traveling. When the load carried by the wheel is greater than that intended for the first springs, the plungers or tread-sections are pushed inwardly until the yokes 58 engage the springs 66, which in the present instance are compression springs, whereupon the latter take up the load in addition to the tension members. If the overload is sufficiently great to overcome the combined resistance of the tension and compression springs, it becomes what may be termed an excess load, and then the sectional tread will be pushed in until its surface corresponds to that of the rigid rim, whereupon the latter assumes the excess load and thus distortion of the springs is avoided. As shown by the drawings, said rim is of substantial wear and pressure-resisting con-

struction, its outer surface being uniformly resistant to wear and pressure at all parts of its exposed surface, that is to say, at its edge portions which are outside the zone occupied by the plungers, and at its intermediate portion constituting said zone.

All parts are quickly and easily accessible, and cheaply and quickly renewable, either in the garage or on the road. In case it is desired to store the vehicle for any extended period of time, it is merely necessary to note what portion of each wheel rim is in contact with the floor, then remove the side plate 18, loosen the nuts on the corresponding rods and unhook the corresponding tension springs, then remove the compression springs, whereupon the rigid rim 30 will bear on the floor, and any danger of causing a set in the springs will be avoided.

Although we have shown the resilient members as provided with tension springs near their outer ends and compression springs at their inner ends, it should be understood that we are not limited to this arrangement, but the relative arrangement of the resilient mechanism may be varied as required.

Having explained the nature of our invention and described one form of device in which it may be embodied, what we claim is:—

1. A wheel having a resilient portion including independently operable tread sections, a hub, spaced apart side members rigidly connected with the hub, and a rigid rim made as a single piece radially perforated to guide said sections, providing a wear-and-pressure-resisting annular rigid tread surface extending entirely across and around the face of the wheel, rigidly connected with said side members and by the latter with the hub for protecting the resilient portion from any undesired burden or overload in excess of a predetermined amount of pressure thereon, and uniformly resistant to wear and pressure at all parts of its tread surface, said resilient portion receding within said protecting rim.

2. A resilient wheel, comprising a rigid rim forming a tread surface extending entirely across the face of the wheel and provided with apertures, a concentric annular web within said rim spaced therefrom and provided with apertures in line with the apertures in said rim, a hub, means for rigidly connecting said rim and web to said hub, plungers guided in said apertures and constituting independent tread sections, resilient means for assuming a predetermined load on said plungers, said rim being arranged to assume any load in excess of said predetermined load and to protect said tread sections therefrom, said tread sections receding within said rim.

3. A resilient wheel, comprising a rigid rim forming a tread surface extending entirely across the face of the wheel and provided with apertures, an integral concentric annular web within said rim spaced therefrom and provided with apertures in line with the apertures in said rim, plungers having their inner and outer ends guided by the apertures in said web and rim respectively, independent tread sections carried by the outer ends of said plungers, springs for assuming a predetermined load on said plungers, said rim being arranged to assume any load in excess of said predetermined load and to protect said tread sections therefrom, said tread sections receding within said rim.
4. A wheel, comprising a rigid rim, a plurality of independent resilient members having provision for assuming a portion of a predetermined load; and resilient means for assuming an additional portion of said predetermined load, said rim being adapted to assume the load in excess of said predetermined load and to protect said resilient members when the load exceeds the sustaining power of said resilient members, said resilient members receding within said rim.
5. A wheel, comprising a rim which is concentric with the axis of the wheel under all conditions of load, a sectional tread composed of independent sections, a set of springs associated with said sections for assuming part of a predetermined load, and other springs arranged to assume the remainder of said predetermined load, said sections being arranged to enter said rim to enable the latter to assume the excess load and prevent further strain upon them when said load exceeds said predetermined load.
6. A wheel, comprising a rim which is concentric with the axis of the wheel under all conditions of load, a sectional tread composed of independently movable sections, a plurality of sets of springs coöperating with said sections for assuming a predetermined load, said rim being arranged to assume the load when said predetermined load is exceeded, said sections receding within said rim and being protected thereby.
7. A resilient wheel, comprising a sectional tread the sections of which are carried by independent reciprocatory members, tension members connected to said reciprocatory members for assuming a portion of a predetermined load, compression members associated with said reciprocatory members arranged to assume the remainder of said predetermined load, and means for assuming any excess load above said predetermined load.
8. A wheel comprising a rigid inner annular member, an outer rim concentric with said inner annular member, a series of independently operable plungers constituting tread sections having their inner and outer

ends guided in said inner member and outer rim respectively, springs connected to said plungers for assuming part of a predetermined load, and other springs for assuming the remainder of said predetermined load, said rim being arranged to assume any load in excess of the predetermined load and to protect said plungers and springs from said excess load.

9. A resilient wheel, comprising a rigid rim, a sectional tread composed of plungers arranged to reciprocate through said rim, springs attached to the inside of said rim and to said plungers for assuming part of a predetermined load, and other springs embracing said plungers and arranged to assume the remainder of the predetermined load.

10. A resilient wheel, comprising a rim having a series of apertures, a series of wearing sections, holders in which said sections are mounted, said holders being guided by said apertures rods to which said holders are attached, springs connected to said rods and to said rim for assuming a portion of a predetermined load, and other springs surrounding said rods and arranged to coöperate with said first mentioned springs to assume an additional load.

11. A resilient wheel, comprising a rim provided with a series of holes, a series of wearing sections, holders in which said sections are mounted slidably fitting said holes, independent radially movable rods to which said holders are attached, springs tending to keep said wearing sections projecting outside of said rim when subjected to a load within predetermined limits, and other springs arranged to assume the remainder of the load, said holders and wearing sections receding within said rim when the wheel is subjected to an overload.

12. A resilient wheel, comprising a rim having a plurality of holes extending therethrough, a sectional tread composed of a series of blocks held in holders, said holders being arranged to slidably fit the holes in the rim, rods affixed to said holders, yokes on said rods, eye-bolts projecting inwardly from said rim, springs connected to said yokes and to said eye-bolts, a cylindrical shelf provided with holes through which the inner ends of said rods pass, and other springs embracing the inner ends of said rods and engaging the outer periphery of said shelf.

13. A resilient wheel, comprising a hub, metal sides attached to said hub, one of said sides being formed with an annular shelf and a rim for the wheel, a series of holders arranged to slidably fit said rim, blocks in said holders, shouldered rods to the outer ends of which said holders are secured, yokes on said rods provided with ears, eye-bolts projecting inwardly from said rim, springs connected to said yokes and eye-bolts, and other springs

embracing the inner ends of said rods and engaging said shelf.

14. A resilient wheel, comprising a hub, sides rigidly attached to said hub, a solid rim extending between said sides and provided with apertures, a shelf intermediate said rim and hub and extending between said sides, said rim and hub forming with said sides an annular chamber, a sectional tread 10 composed of sections sliding through said rim and guided by said apertures, resilient members connected to said sections for assuming a portion of a predetermined load, and other resilient members for assuming an 15 additional load, said resilient members all being housed in said chamber, whereby when the combined sustaining power of said resilient members is exceeded the excess load is borne by said rim.
- 20 15. A wheel having resilient portions operating independently thereof, each guided at a plurality of points and having means for assuming a predetermined load on said portions, a hub, spaced apart side members 25 rigidly connected with the hub, and a radi-

ally perforated rim formed in a single piece having a wear and pressure-resisting tread surface extending entirely across and around the face of the wheel, rigidly connected with said hub and uniformly resistant to wear and pressure at all parts of its tread surface, and a concentric annular web within said rim spaced therefrom and rigidly connected thereto, said web and rim constituting the outer and inner walls and the side members 30 35 constituting the side walls of an annular chamber in which the resilient elements of the wheel are housed, said hub and rim being adapted to assume any load in excess of said predetermined load to protect said resilient portions when the latter recede within said tread surface under the action of the excess load.

In testimony whereof we have affixed our signatures, in presence of two witnesses.
